UNITED STATES PATENT OFFICE.

JULIUS HAHN, OF DETROIT, MICHIGAN, ASSIGNOR TO TRUSSSED CONCRETE STEEL COMPANY, OF DETROIT, MICHIGAN, A CORPORATION OF MICHIGAN.

FLOOR CONSTRUCTION.

No. 886,997.

Specification of Letters Patent.

Patented June 29, 1909.

Application filed July 18, 1908. Serial No. 444,292.

To all whom it may concern:

Be it known that I, Julius Hahn, a citizen of the United States, and a resident of Detroit, in the county of Wayne and State of Michigan, have invented a new and Improved Floor Construction, of which the following is a specification.

This invention relates to the construction of reinforced concrete floors and ceilings, 10 and the object of these improvements is to provide a floor of minimum thickness for a given carrying capacity.

This invention consists in a novel reinforcement for flat floor slabs and comprises 15 two series of diagonal rods or bars crossing each other at about the center of each floor panel, together with properly disposed I beams at the points of support.

It further consists of novel auxiliary reinforcing members for the concrete in the immediate vicinity of the floor supports.

In the accompanying drawings, Figure 1 is a plan of a section of reinforcements for a floor slab. Fig. 2 is a diagrammatic elevation of the main supports, showing their position in the floor. Fig. 3 is a view of the reinforcing members immediately around a pillar.

Similar reference characters refer to like parts throughout the several views.

In the structure shown, no account is taken of the construction of the columns which may be of reinforced concrete, steel, cast-iron or any other desirable material. I beams 1 extend across the centers of the posts and are joined by shorter pieces 2, all connected by plates 3 and angles 4. Engineers can modify this construction to suit requirements, the invention comprising merely 40 bars of sufficient strength extending preferably at right angles to each other from the posts, and provided with the lower flanges of the usual I beam, and of less width than the thickness of the floor so that the lower 45 flange will not be exposed. These I beams form the center of a plate of concrete; to further reinforce this plate a series of short rods are employed, some of which are formed to extend over the upper flange of the I 50 beams as shown at 5 in the drawings. Ties 7 may be punched in the webs of the I beams, and the other rods 6 extended therethrough, none of the rods however depending below the lower surface of the I beams. The number 55 of the rods depends upon the various condi-

tions under which the floor is constructed, and whether any of either rods 6 or 8 be omitted will be determined by the constructing engineer. Sufficient reinforcement must be provided to render the concrete between 60 the I beams of sufficient strength to support the floor slab under the given conditions of loading. Extending diagonally across the slabs are two series of rods 9, each rod of each series extending practically from I 65 beam to I beam. The rods 8 may be bent down to furnish supports for the ends of the rods 9 during the forming of the slab. Smaller rods 10 may be laid on the rods 9 across the open spaces to reinforce the small 70 squares.

It will be noticed that this construction comprises a central plate of great strength where floor panels are usually weakest. It further comprises cantilevers at the supports 75 which shorten the usual spans and are of such strength that there is little danger of the post punching through. It further comprises a construction wherein every detail can be determined by calculation and by the 80 many experiments in this art so that no material need be wasted.

At side walls and corners, the outer I beam may be short and support the outer walls.

Concrete is rammed around the various rods to form the floor slab, as shown at 11 in Fig. 2, the usual false-work being employed. It will be noticed that this slab will have no projecting beams or bosses on either 90 side, giving a smooth ceiling.

The rods may be of any desired design, such as smooth, twisted or distorted, and of any desired cross section.

Having now explained my improvements 95 what I claim as my invention and desire to secure by Letters Patent is:—

1. In a floor construction, the combination of short horizontal I beams rigidly secured together in the form of a cross at each post, 100 short reinforcing rods extending across the spaces between the arms of the crosses, main reinforcing rods in two series extending between crosses diagonally across the floor panels and crossing at about the middle of 105 each panel, auxiliary rods extending across the spaces between the main rods, and concrete molded around the reinforcements to form a slab having unbroken upper and lower surfaces.

2. In a floor construction, the combination of horizontal metal beams rigidly secured together in the form of a cross at each point of support, reinforcing members disposed in the spaces between the arms of each cross, main reinforcing members extending across the spaces between the supports and crossing each other, and concrete molded around all the reinforcing members to form a flat slab.
3. In a floor construction, the combination of short metal horizontal beams rigidly secured together at an angle to each other at the points of support for the floor and short rods between the same, a series of parallel main tension members extending diagonally across each panel between the points of support, a similar series of parallel tension members crossing the first at about the middle of the panel, auxiliary members placed across the spaces between the several series of main tension members, and concrete molded around the various members to form a flat slab.
4. In a floor construction, the combination of short horizontal beams secured together at an angle to each other at each point of

support, and having holes in their webs, rods projecting through said holes across the spaces between the beams, main tension members extending diagonally across the floor panels and resting on said rods, and concrete molded around the reinforcing members to form a slab.

5. In a floor construction, the combination of short horizontal metal I beams intersecting each other to form a cross at each point of support, short reinforcing rods extending between the arms of each cross and resting thereon, main reinforcing tension members extending across the spaces between the supports, some of said members crossing each other at about the middle of each panel, and concrete molded around the I beams, reinforcing rods and main tension members to form a flat slab.

In testimony whereof, I have signed this specification in the presence of two subscribing witnesses.

JULIUS KAHN.
